UNITED STATES PATENT OFFICE.

HERMANN GEHNRICH, OF NEW YORK, N. Y.

POR TABLE OVEN.

1,104,652.

Specification of Letters Patent.

Patented July 21, 1914.

Application filed July 13, 1911. Serial No. 638,206.

To all whom it may concern:

Be it known that I, HERMANN GEHNRICH, a citizen of the United States, residing at New York, county of New York, State of New York, have invented new and useful Improvements in Portable Ovens, of which the following is a specification.

This invention relates to a portable oven which is built up of a number of sections, 10 and can be used for various purposes such for example as baking japan, lacquer, or enamel on metals or for treating metal known under the name of sherdizing.

The invention consists in the novel 15 method of heating the oven, the heat being conducted into a series of flues located at each side of the oven. These flues are connected to an upper heat compartment or conduit and to a lower fire compartment.

20 The heat in passing upwardly from the fire compartment radiates into the oven. The flame being inclosed within the fire compartment, the upper conduit, and the flues, will not come into contact with the 25 articles in the oven and danger of fire is thus avoided.

The sectional casing is designed to form the walls of the oven, with the fire compartment and heat compartment located 30 within the lower and upper portions of the oven, while the connecting flues extend from the fire compartment upwardly alongside of the inner walls of the casing and being separated from the casing the entire surface 35 of the flues will freely diverge the heat directly into the oven. A chimney is connected to the upper portion of the oven and it has a swivel damper, the handle of which engages a bracket fixed to the door of the 40 oven. This arrangement prevents the door from being opened until the damper is swiveled or opened. The oven has air inlet pipes extending through the fire compartment, the air thus admitted into the oven 45 is warm.

The novel features of the invention are more fully described in the following specification and claims and illustrated in the accompanying drawings in which—

50 Figure 1 represents a front elevation partly in section of a furnace embodying this invention. Fig. 2 is a vertical section taken along the line $\alpha-\alpha$ of Fig. 1. Fig. 3 is a horizontal section taken along the line $y-y$ Fig. 1. Fig. 4 is a detail section of a baffle plate taken along the line $z-z$ Fig. 1.

Fig. 5 is a detail front elevation of a damper connection.

In this drawing the letter a designates an oven which is built up of a number of sections b . These sections have double walls with a non-heat conductor located between the walls and each section is removable so that the oven can be taken down. The oven has swinging doors c hinged at the front 60 of the casing. At the lower part of the oven is situated a fire compartment d which is divided from the oven by means of a plate e and this plate is bolted to the bottom of the oven. The plate extends across the oven 65 and it has connected to it a series of flues f extending upwardly and connected to the upper conduit or compartment g . This conduit has a chimney h to lead off the products of combustion.

A series of gas inlet pipes i each pipe having a burner tube communicating with the interior of the lower compartment and each burner tube can be lighted to furnish heat to the oven. A series of inlet openings j 70 furnish air to the flame of the burner tubes.

A series of baffle plates k are positioned over the burner tubes and deflect the flames toward the flues. Each of these baffle plates is fastened to the plate e by means of bolts m 85 best seen in Fig. 4. A number of pipes n extend up through the fire compartment d into the oven, these pipes being adapted to conduct air from the exterior of the furnace into the oven. It will be seen that 90 these pipes are heated by passing through the fire compartment and the air passing into the oven will thus be heated. To the upper portion of the oven is connected a chimney o having a damper p with a handle q extending to the front of the furnace. When the damper is closed the handle engages a bracket r fixed to the swinging door c best seen in Fig. 5.

It will be understood that the door cannot be opened until the handle is turned thus swiveling the damper to its open position. It will be seen that the heat in passing from the fire compartment into the flues and the upper conduit is radiated into the 105 oven.

In the foregoing construction the outer casing constitutes the upper, lower and side walls of the bake compartment of the oven with the fire compartment, heat compartment and flues arranged in the interior of the bake compartment of the oven. By

having all the heat producing and conducting elements arranged within the outer walls the heat generated circulates directly into the bake compartment without first heating any intermediate walls.

I claim:

1. In a portable oven, the combination with a casing adapted to constitute the upper, lower and side walls of a bake compartment; a heat compartment arranged within the upper part of the bake compartment; a fire compartment arranged within the lower part of the bake compartment; a series of flues situated in the bake compartment, separated from the walls and extending from the fire to the heat compartment; devices for heating the fire compartment; and a chimney leading from the upper compartment.
2. A device of the kind described, comprising a sectional casing with a swinging door, an oven located within the casing, means for heating the oven, a chimney connected to the oven, a damper arranged in the chimney, and means carried by the dam-

per for locking the door while the damper is closed.

3. A device of the kind described, comprising a sectional casing with a swinging door, an oven located within the casing, means for heating the oven, a chimney connected to the oven, a swivel damper arranged in the chimney, and means coöperating with the damper and the door for locking the door while the damper is closed. 35

4. A device of the kind described, comprising a sectional casing with swinging door, an oven located within the casing, means for heating the oven, a chimney connected to the oven, a swivel damper arranged in the chimney and means coöperating with the handle of the damper and the door for locking the door when the damper is closed. 40

In testimony whereof I have hereunto set my hand in the presence of two subscribing 45 witnesses.

HERMANN GEHNRICH.
